E. SAUNDY.

SKATE.

APPLICATION FILED SEPT. 8, 1920.

1,367,328.

Patented Feb. 1, 1921.

Edward Saundy, Inventor
By Seymour and Lub. Atty.

UNITED STATES PATENT OFFICE.

EDWARD SAUNDRY, OF NEW HAVEN, CONNECTICUT.

SKATE.

1,367,328.

Specification of Letters Patent.

Patented Feb. 1, 1921.

Application filed September 8, 1920. Serial No. 408,995.

To all whom it may concern:

Be it known that I, EDWARD SAUNDRY, a citizen of the United States, residing at New Haven, in the county of New Haven, and 5 State of Connecticut, have invented a new and useful Improvement in Skates; and I do hereby declare the following, when taken in connection with the accompanying drawings and the characters of reference marked 10 thereon, to be a full, clear, and exact description of the same, and which said drawings constitute part of this application, and represent, in—

Figure 1 is an underside view of a portion 15 of a skate constructed in accordance with my invention.

Fig. 2 is a transverse sectional view of the same.

Fig. 3 is a detached view of one end of 20 the screw showing the key handle and means for holding it in its retired position.

Fig. 4 is a side view of the same.

Fig. 5 is a longitudinal sectional view of 25 the screw and the key showing the key in retired position.

Fig. 6 is a similar view showing the key in an extended and screw-operating position.

Fig. 7 is a sectional view on the line 7—7 30 of Fig. 5.

Fig. 8 is a sectional view on the line 8—8 of Fig. 5.

This invention relates to an improvement 35 in skates, either ice or roller, and particularly to skates which are secured to the shoe by means of clamps moved by a right and left-hand screw.

The object of this invention is to mount a 40 key in the screw so that it will always be convenient for use, and the invention consists in the construction as hereinafter described and particularly recited in the claims.

In carrying out my invention I employ the 45 usual toe-piece 10, mounted in the usual manner upon a runner 11. Supported in the usual way is a right and left-hand screw 12 formed with an external grooved rib 13, by which it is held against longitudinal 50 movement. The usual clamps 14 and 15 are mounted on this screw to be moved thereby. This screw is formed with a round, longitudinal passage 16, forming a shoulder 17 near one end, which end is formed with an angular hole 18. Into the passage is inserted a 55 key stem 19, preferably round in cross section so as to pass through the hole 18,

through which it projects and to which end a handle 20 is secured as herein shown by set-screw 21. The opposite end of the stem 60 is formed with a round head 22 corresponding to the recess 16, and within the head, with an angular neck 23 corresponding to the hole 18. When it is desired to turn the screw to adjust the clamps, the key stem is 65 drawn outward until the neck 23 enters the hole 18, and the withdrawal of the key is prevented by the engagement of the head 22 with the shoulder 17. The handle 20 is formed with wings 24 and 25 which may be 70 entered beneath spring fingers 26 and 27 when in the retired position.

With this construction the key is always ready for use and it is only necessary to draw it out so that the neck 23 engages with 75 the hole 18 to provide means for turning the screw 12. Thus the possibility of losing a key in key-adjusting skates is avoided.

I claim:

1. In a screw-clamp skate, the combination with a right and left-hand screw formed with a longitudinal opening of clamps mounted on said screw, a key mounted in said screw and longitudinally movable therein, and means for engaging the key with one 80 end of the screw.

2. In a screw-clamp skate, the combination with a right and left-hand screw of clamps mounted thereon, said screw formed with a longitudinal opening communicating with an angular hole at one end, a key stem arranged within said screw and projecting through said opening, said stem formed at its inner end with an angular neck fitting said hole, and provided at its outer 90 end with a handle.

3. In a screw-clamp skate, the combination with a right and left-hand screw of clamps mounted thereon, said screw formed with a longitudinal opening communicating with an angular hole at one end, a key stem arranged within said screw and projecting through said opening, said stem formed at its inner end with a head and an angular neck fitting said hole, and provided at its outer 100 end with a handle, and spring fingers engaging with the ends of said handle.

In testimony whereof, I have signed this specification in the presence of two subscribing witnesses.

EDWARD SAUNDRY.
